UNITED STATES PATENT OFFICE.

CLIFFORD F. HUFF, OF HAVANA, ILLINOIS.

APPARATUS FOR HOISTING AND LOWERING PAINT-RECEPTACLES, &c.

1,315,502.

Specification of Letters Patent.

Patented Sept. 9, 1919.

Application filed April 4, 1919. Serial No. 287,479.

To all whom it may concern:

Be it known that I, CLIFFORD F. HUFF, a citizen of the United States, residing at Havana, in the county of Mason and State 5 of Illinois, have invented certain new and useful Improvements in Apparatus for Hoisting and Lowering Paint-Receptacles, &c., of which the following is a specification, reference being had therein to the accompanying drawing.

This invention relates to new and useful improvements in apparatus for raising and lowering receptacles used in paint mixing machines and so forth, and consists essentially in the provision of means for winding up belt connections with a carriage on which the receptacle is placed, and for holding the carriage in different positions.

The invention consists of an apparatus 20 having various details of construction, combinations of parts as will be hereinafter more fully described and then specifically defined in the appended claims.

My invention is clearly illustrated in the 25 accompanying drawings, which, with the letters of reference marked thereon form a part of this application and in which similar letters of reference indicate like parts in the views in which,

30 Figure 1 is a front elevation of the machine.

Fig. 2 is a side view, and

Fig. 3 is a detail view.

Reference now being had to the details of 35 the drawings by letter A designates the frame of the apparatus having standards or beams B with cross pieces at the upper portions thereof upon which a motor C is fastened for supplying power to drive the mixer 40 shaft D which is journaled in suitable bearings in cross pieces of the frame. A counter shaft E is journaled in the frame and has a wheel E' keyed thereto which has belted connection with a pulley C' fixed to the 45 motor shaft, and F is an idler bearing against the belt G to keep same taut. Said counter shaft has keyed thereto a balance wheel H, and at one end is a bevel gear I in mesh with a similar gear D' keyed to the 50 shaft D. Stirrer blades of any shape and designated by letter L, are adjustably held upon the shaft D by means of set screws L' adapting same for convenient use as may be desired.

55 A carriage O, has upright pieces O' movable one on either side of the beams B and

which are connected by a cross piece O² and which serve to guide the carriage as the latter is raised and lowered. Upon said carriage the receptacle Q adapted to contain the 60 ingredients to be mixed is supported.

A shaft P is journaled in suitable bearings in the frame and upon which belts R are adapted to wind, as shown clearly in the detail view, Fig. 3, of the drawings, for 65 the purpose of elevating the carriage or lowering the same when the straps unwind. Fixed to the shaft P is a gear wheel R' in mesh with a small pinion wheel S fixed to a pin S² journaled in an aperture in the end 70 of the arm S', which latter is fixed to a hollow shaft S³ journaled upon a headed pin S⁵ which is fixed to the standard B. Said hollow shaft has an integral finger S⁴ to which the upper end of the coiled spring S⁷ 75 is fastened, while the lower end of said spring is secured to a bracket S⁶ upon the standard. A handle S¹⁰ has an arm which is fixed to said pin S² and serves as a means for rotating the pinion S. By the provision 80 of the coil spring S⁷ it will be noted that the pinion S will be held frictionally in mesh with the teeth of the gear R' and serving as a brake mechanism by reason of the friction intermediate the intermeshing gears. 85

In operation, the ingredients to be mixed are placed within the receptacle, and through the medium of the motor the paddle or stirrer carrying shaft may be rotated, the paddles being adjusted to the locations desired. The operator may by the hand lever, cause the receptacle to be raised to the desired elevation, to cause the paint materials to be thoroughly mixed. By the provision 90 of an apparatus embodying the construction 95 of my invention, a simple and efficient means is afforded whereby large quantities of paint materials may be easily, thoroughly and quickly mixed, the parts being made adjustable to facilitate the thoroughness of the 100 work.

While I have shown a particular form of apparatus embodying the principle of my invention, it will be understood that the details of the construction of the apparatus 105 may be varied if desired without departing from the spirit of the invention.

What I claim to be new is—

1. In combination with a frame having vertically disposed beams spaced apart, a 110 shaft journaled in suitable bearings in said frame, a carriage having upright pieces one

mounted upon either side of a beam, bars outside the beams and connecting said upright pieces, and coöperating with the latter to guide the carriage as it is raised and lowered, and belts fastened at their lower ends to said bars and adapted to wind upon said shaft.

2. In combination with a frame having vertically disposed beams, a vertically movable carriage mounted between the latter, and means for guiding the carriage as it is raised and lowered, a shaft journaled in said frame, belts secured at their lower ends to the carriage and their upper ends winding

upon said shaft, a gear fixed to said shaft, 15 an arm pivotally mounted upon the frame, a pinion journaled upon the arm and in mesh with said gear wheel, a crank handle fixed to said pinion, said arm having an integral finger, a spring fastened at one end 20 thereto and its other end to the frame.

In testimony whereof I hereunto affix my signature in presence of two witnesses.

CLIFFORD F. HUFF.

Witnesses:

GEO. W. WHITE,
EDMUND P. NISCHWITZ.
